UNITED STATES PATENT OFFICE.

LORENZ F. MUTHER, OF NEWTON CENTER, MASSACHUSETTS.

PRESSING DEVICE.

Application filed October 28, 1922. Serial No. 597,519.

To all whom it may concern:

Be it known that I, LORENZ F. MUTHER, a citizen of the United States, residing at Newton Center, in the county of Middlesex 5 and State of Massachusetts, have invented a new and useful Improvement in Pressing Devices, of which the following is a specification, reference being had therein to the accompanying drawings.

10 This invention relates to a pressing device for use on folding machines of the general type shown in the joint application for Letters Patent filed in the United States Patent Office by Lorenz Muther and 15 Frederick S. Glines on July 24, 1922, Serial No. 576,965.

The main object of the invention is the provision of a pressing device for folding machines in which the work engaging portion 20 is capable of adjustment in relation to the other folding instrumentalities in order to take care of work of varying character.

Other objects of the invention will be more specifically set forth and described 25 hereinafter.

Briefly, my invention contemplates the provision of a pressing member in which the work-engaging portion is made adjustable with relation to the main body or arm 30 of said member; this adjustment being preferably in a direction transverse to the normal line of feed of the machine. By this means, the pressing member may be adapted to varying conditions of work, 35 such as variations in the width of binding tape used and in the radii of the convex curved portions of the work.

In the accompanying drawings, Fig. 1 is 40 an end elevation of a portion of a folding machine of the type above referred to showing a pressing device constructed and operated in accordance with my invention applied thereto; Fig. 2 is a side elevation of said portion of said machine as viewed 45 from the operator's position; Fig. 3 is a sectional view on an enlarged scale of the pressing member on line 3—3 in Fig. 1; and Fig. 4 is a view in perspective on an 50 enlarged scale of the work engaging portion of said pressing member.

Referring to the drawings, 15 indicates the lower arm of the machine, 20 a feed bar mounted in a housing 22 and adapted for reciprocation in said housing and for 55 forward and backward movement for feeding the material. The feed bar 20 con-

operates with an idler roll 21 held in place by a screw stud 32. A guide bar 35 having its lower arm formed with a guiding edge 36 is held in a depending position 60 over the work. 50 indicates a work support having a bevelled edge 51 toward the operator upon which is mounted the wiper 53 having a portion 54 bent under the work plate and a thin edge 55 turned up and 65 slightly hooked over, said edge being oblique with the normal line of feed, and 58 indicates a plow or turner. All of the foregoing parts and the functions and mode of 70 operation are fully shown and described in said Muther-Glines application.

The novel features of my invention reside in the provision of a pressing member having an adjustable work-engaging portion. In the form of the invention shown, the presser-arm 60 is provided with a transverse end-piece 92 having a longitudinal open groove 93 in its lower face which is adapted to receive a tongue 94 formed on the upper face of a work-engaging portion 95. Any suitable means may be employed for locking the portion 95 in adjusted position upon the end-piece 92 such as a headed screw 96 mounted in a slot 97 in said end-piece and adapted to engage a 80 threaded hole 98 in the portion 95. The head of the screw 96 overlaps the sides of the slot 97 and thereby when tightened holds the work-engaging portion in tight 85 engagement with the end-piece. The work-engaging portion may be of any suitable 90 contour but as shown is provided with a toe-portion 99 extending toward the operator.

In the use of folding machines of this 95 character, it is important that the pressing member be so located with respect to the plow or turning member, that the turned over portion be pressed down upon the reverse side of the material without subjecting the turned-over portion to undue strain. It has been found as a general rule that better results are accomplished by a close 100 grouping of the folding instrumentalities so long as such grouping does not affect the 105 natural curve of the turned over edge, or cause a bunching of the binding. Under such conditions, however, if a wide binding 110 be used and the pressing member is close to the plow, there is a tendency for the binding to be crowded between the plow and presser. This causes the binding to buckle

or wrinkle thereby preventing a smooth fold being obtained and which difficulty may, however, be overcome by moving the pressing-member away from the plow sufficiently to allow the wide binding to fold over without bunching. By making the work-engaging portion of the pressing member adjustable my pressing device may be adapted for bindings of different widths.

10 It is to be noticed that the adjustment may be easily and expeditiously made by the operator merely by manipulation of the screw 96. The loosening of the screw permits the work-engaging portion to be moved into proper position to suit the particular kind of binding when the tightening of the screw completes the adjustment.

What I claim is:—

1. In a folding machine, the combination of means for feeding material having a binding attached to the edge thereof, a plow for turning said binding around the edge of said material and means arranged forward of the plow and in close proximity thereto for pressing said turned binding upon the body-portion of said material; said pressing means comprising a pivotally mounted arm provided with a transverse

end-piece having a longitudinal slot therethrough and a longitudinal groove in its lower face, a work-engaging portion having a longitudinal tongue fitting said groove and a screw located in said slot and having its end threaded in the said work-engaging portion for securing said work-engaging portion in adjusted position on said end-piece, said work-engaging portion having a toe-portion encircling the nose of said plow.

2. In a folding machine, the combination of means for feeding material having a binding attached to the edge thereof, a plow for turning said binding around the edge of said material and means for pressing said turned binding upon the body portion of said material, said pressing means comprising an arm, a work-engaging portion mounted on said arm forward of the plow and in close proximity thereto and provided with a toe portion encircling the nose of said plow, said work-engaging portion being normally fixed on said arm but capable of adjustment in a direction transverse to the normal line of feed.

In witness whereof, I hereunto set my hand this 14th day of October, 1922.

LORENZ F. MUTHER.
